UNITED STATES PATENT OFFICE

HUGH C. MACDOUGALL, OF WEST NEW YORK, NEW JERSEY, ASSIGNOR TO FRANKLIN BAKER COMPANY, OF HOBOKEN, NEW JERSEY, A CORPORATION OF NEW JERSEY

ART OF SHELLING COCONUTS

Application filed April 27, 1929. Serial No. 358,461.

My invention relates to the art of shelling nuts, and especially coconuts, and includes both processes and mechanism for this purpose.

- 5 The general object is to shell the nuts rapidly and economically, with little or no damage to the meats (or kernels), which are delivered intact with their contained "milk", and completely freed from shell.
- 10 As to the process, the principal novelty consists, (after preliminary steaming or other suitable softening treatment, preferred in most cases) in cutting an annular groove or kerf in the nut near each end, thus defining 15 a practical separation of each end or "polar" piece of the shell from the central "zone," or "belt"; then pressing or compressing the central portion axially by force applied to its edges, thus bulging the central portion, or 20 at least holding it under compression, and while so bulged or held, hammering said central portion and more-or-less concurrently, expanding its ends, so that the central shell belt is cracked and split away; the ends or 25 "pole" pieces, or caps are then removed, this removal being, in machine operations, usually accomplished or accompanied by applying compressive force edgewise to crack and disrupt these shell pieces. The meat remains 30 intact and undamaged.

As to the machine, the principal novelty consists in a suitable feeder, or conveyor, having chucks or holders to facilitate the proper positioning of the nuts; grooving mechanism 35 to which the nuts are supplied in proper positions by the feeder; and cracking mechanism, to which the grooved nuts are delivered by the grooving mechanism, and in which the shells are cracked and freed from 40 the meats.

The characteristics and advantages of the invention are further sufficiently explained in connection with the following detail description of the accompanying drawings, which show certain exemplifying embodiments. After considering these examples, skilled persons will understand that many variations may be made, and I contemplate 45 the employment of any structures or opera-

tions that are properly within the scope of the appended claims.

In the drawings:

Fig. 1 is a side view of a typical coconut.

Fig. 2 is a longitudinal section.

Fig. 3 is a perspective view of the nut after grooving.

Fig. 4 is a longitudinal section of Fig. 3.

Fig. 5 is a similar section, showing the belt bulging operation.

Fig. 6 shows the belt cracked and partly disrupted.

Fig. 7 shows the nut after removal of the shell belt.

Fig. 8 is a longitudinal section of one end 55 of Fig. 7.

Fig. 9 is a perspective view of one end, showing the shell cap cracked or crushed by edge pressure.

Fig. 10 is a section of the same.

Fig. 11 is a longitudinal section of the shelled meat, or kernel.

Fig. 12 is a vertical, longitudinal section of the machine.

Fig. 13 is a top plan of a detail of the feed 75 conveyors.

Fig. 14 is a section at 14—14, Fig. 13.

Fig. 15 is a section, in the plane of its shaft axis, of the grooving mechanism.

Fig. 16 is an enlarged section of one of the 80 grooving units.

Fig. 17 is a view from the left of Fig. 15 or 16.

Fig. 18 is a section at 18—18, Fig. 15.

Fig. 19 is a detail of the grooving conveyor.

Fig. 20 is a section at 20—20, Fig. 19.

Fig. 21 is an enlarged section of the cracking mechanism, in the plane 21—21, Fig. 12.

Fig. 22 is an elevation, in the plane 85 22—22, Fig. 21, of one of the cracking units.

Fig. 23 is an enlarged detail thereof.

Fig. 24 is a section at 24—24, Fig. 21.

Fig. 25 is a perspective view, enlarged, of the cam mechanism for operating the shell belt 88 grippers.

Figs. 26 and 27 are partial axial sections of one of the cracking units, showing successive positions of the parts.

Fig. 28 is an axial section of a complete 100

cracking unit, with the parts in a position subsequent to that of Fig. 27.

Figs. 29, 30 and 31 show other successive positions of the cracking unit, completing 5 their operative cycle.

Fig. 32 is an elevation of one cam drum.

Fig. 33 is a diagram of the cam actions, or "cycle", of the cracking mechanism.

Fig. 34 is a section of a modified cracking 10 mechanism, the modification relating mainly to the anvil actuating means.

The shelling process is illustrated in Figs. 1 to 11, and the mechanism performs the process operations in the order there shown, 15 and as now described.

A typical coconut 1, after hulling, as shown in Figs. 1 and 2, is approximately oval in axial section; the dimensions vary considerably, and there are also irregularities in the 20 shell form, such as the local depressed portion, or lump 2, and "polar" projections or elongations such as 2^a; and the machine is designed to allow for these variations and irregularities. The shell 3 is thick, hard and 25 tough. The kernel or "meat" 4 inclosing the "milk" 4^a, lies closely against the inner shell surface and the shell, or shell fragments, tend to adhere to it. On account of these 30 characteristics, it has been difficult and expensive, by previously known means or methods, to remove the shell while keeping the meat intact, as is desired for many purposes and reasons, as understood in the art. The present process and machine have been 35 developed to quickly and economically shell the nuts while preserving the meats in complete, intact condition, and without any appreciable injuries.

After soaking or steaming to soften the 40 shell, a circular kerf or groove 5 is first cut near each end, in the nut, the general plane of the grooves being perpendicular to the nut axis, and preferably these grooves pass entirely through the shell, thus separating it 45 into three parts: a central part 6 hereafter identified (for convenience) as the "body" or "belt", and two substantially similar end pieces, 7 hereafter called "caps". Although 50 divided, these parts are still quite tenaciously adherent to the meat, the caps by reason of 55 adhesion, and the belt by adhesion and its spherically arched form, enclosing a spherical section of the meat. The grooves are cut, so far as the process is concerned, by any suitable tool; in the present machine, the cutting tools 8 are analogous to milling cutters, so that the cross sectional form of the groove is determined by the form of the cutter. The 60 grooves are preferably of "undercut" form; that is, as here shown, each is, in section, practically of narrow, cylindrical form, the center of such cylinder being at the axis of the nut; thus there is produced at each end of the belt 6 an edge or flange 9 having its 65 inner surface 10 longitudinally directed. In

order to insure the complete severance of the shell sections, a slight penetration of the cutters into the meat is practically unavoidable; such penetration produces minute annular channels 11 in the surface of the shelled meat (Figs. 9 and 11), which are of more-or-less uniform character and do not weaken the meat structure or interfere with its subsequent cutting into any desired shapes, and in brief, are unobjectionable. 75

The belt 6 is now to be split or broken up sufficiently to free it from the meat, and while broadly, any suitable means or procedure may be employed for this purpose, specifically I have found it most desirable to split the shell by hammer blows; and to prevent such hammering from damaging the meat, the belt is longitudinally compressed, preferably to such an extent as to bulge it, and especially to bulge its equatorial portions, producing an inner clearance from the meat, as at 12, Fig. 5. This compression and/or bulging is produced (so far as the process is concerned) by application of any suitable tools or implements in or to the groove formations 5, or to the belt-ends 9; in the machine, such implements are segmental grippers 13, which have end-portions 14, conforming to the grooves and engaging the diagonal groove-faces 15; and the gripper bodies may also have shoulders 16, engaging the belt-ends 9. The grippers are moved axially to effect entry, and to produce the bulge (Fig. 5); the belt portion is hammered, by blows directed mainly upon its equatorial zone, with force sufficient to split the shell (Fig. 6), and concurrently, or thereafter, the grippers are moved outward, or radially, to similarly move the split end portions of the shell belt and disrupt the shell into pieces 105 6^a, which fall away from the meat. The splitting and removal of the belt portion of the shell may thus be a result of hammering, or of disruptive radial movement of end portions thereof, or, preferably, may result from 110 the combined operations. The nut is then in the condition shown in Figs. 7 and 8.

The end caps 7 are now gripped peripherally (by means included in the machine, but not shown in the "process" views) and crushed by pressure directed radially inward 115 (Figs. 9 and 10) and the fragments fall away, leaving the meat 4, (Fig. 11) completely freed of shell, intact, with contained milk, and undamaged, ready for any desired utilization or disposition.

The machine, which in its action performs the process operations (as well as other or incidental operations) as above described, as 120 illustrated in Figs. 12 to 33, is built upon or about a main frame comprising legs 20, horizontal longitudinal members 21, and cross members 22 and 23, with cross ties or braces where necessary, and consists of three principal sections (Fig. 12): a feeder 25, a groover 125

26 and a sheller or cracking mechanism 27. While intermittent drive might be employed for some or all sections of the machine, continuous drive is here provided for, so that the 6 nuts move continuously and rapidly through the machine.

The feeder (Figs. 12, 13 and 14) consists of a chain conveyor 28, carrying a series of regularly spaced double chucks 29, each 10 chuck consisting of a cup 30, to receive one end of the nut. The cups are carried by rods 31, slidably mounted in sleeves 32, of a yoke 33, and prevented from rotating by a spline connection 34. The lower part of each yoke 15 has ears 35, secured as by screws to inner links 36, of the chain conveyor. The conveyor also includes outer links 37, and pivot rods 38 carrying at their outer ends rollers 39. The path of movement of the conveyor 20 may vary, but preferably, for reasons which will appear, its upper, active stretch 40, Fig. 12, moving in the direction of the arrow, includes a horizontal portion 41 located at convenient height for one or usually a number 25 of workmen located along it, to place the coconuts in the chucks. The machine can and usually will be operated at high speed and usually therefore two or more workmen may be required to insure the filling of all of 30 the chucks as they advance, and the loading stretch 41 of the conveyor will be made as long as necessary for that purpose, as indicated by a portion broken away in the drawings. At the end of the horizontal stretch 35 there is an upwardly inclined portion in order to bring the nuts to a desired position for delivery to the grooving mechanism 26, when that is in the location shown. For this conveyor arrangement, it is supported by 40 three pairs of sprockets 42, 43 and 44, mounted on shafts 45, 46 and 47; shaft 45 is carried in bearings at the top of tall standards 48, and shafts 46 and 47, are carried by shorter standards 49 and 50. The sprockets have 45 notches 51, in which the chain rollers 39, engages; and the bend in the conveyor between the straight portion 41 and the upwardly inclined portion 52, is guided or directed by lower guide rails 53, and the upper guide rails 54, which engage the chain rollers 29. The return stretch of the conveyor is guided by the sprockets 43. These are also the driving elements of the conveyor and are themselves driven by a gear 55, on their shaft 46, engaging 55 a gear on a countershaft 57, to a shaft 58, supported in bearings 49, below frame members 60.

The initial driving member of the entire machine is a shaft 61, carried by bearings 62, on frame uprights 20, and driven by an independent electric motor or a pulley and belt 63, from a countershaft. This shaft 61 is connected through double-reduction gearing and a countershaft 64, to shaft 58, for driving the feeder conveyor 28, just above mentioned.

The chuck cups are operated by levers 65, having forks 66 engaging studs 67, on the cups and fulcrumed at 68, on the yoke. Springs 69, are stretched between pins 70, on the levers and pins 71, inserted in the yoke, 70 to move the cups convergently until stopped by washer 72 on the ends of rods 31. The lower ends of the levers have rolls 73 which cooperate with cams 74, connected to upper parts of the standards 48, and acting on the rolls when the chuck reaches the position shown at the right of shaft 45, in Fig. 12, as the nut held in the chuck is about to be grasped by grippers on the conveyor of the grooving mechanism, to move the levers and 75 retract the cups outwardly, thus freeing the nut, which passes on in the grooving conveyor. The cups are then held in retracted positions by detent mechanism consisting of bell crank levers 75, fulcrumed on pins 71, above mentioned and having their short arms 76, connected by a link 77. Each lever has a tooth 78, to cooperate with a pin 79 on one of the levers 65. In the case of the lever at the left of Fig. 14 this pin may be an extension of spring holding pin or screw 70; and in the case of the lever shown at the right of Fig. 14, 79, is the detent pin. The long arms of the levers have springs 80, urging them to engage the detent pins, and these lever arms extend to convenient positions for operation by a workman standing at either side of the conveyor.

As the chucks 30, start along the upper straight stretch of the conveyor the cups are in retracted position and so held by the detent mechanism, ready to receive a nut. After the nut is located between the cups either of the levers 75, is moved, up or down as the case may be, to release levers 65, whereupon springs 69, act to move the cups inward and engage the nut and hold it in properly centered relation in respect to the conveyor, the range of movement of the chuck members being such as to accommodate the variations in nut length. As each chuck reaches the position at the right of Fig. 12, the nut is released in the manner above described and passes on in the grooving conveyor, for the grooving action.

The grooving mechanism, Figs. 12, and 15 to 20, includes a conveyor and grooving mechanism proper. The conveyor 90, Figs. 12, 15, 19 and 20, consists of chain links 91, connected by cross bars 92, with spacer sleeves 93, and having rollers 94, on their outer ends. The rollers engage in the tooth spaces of upper sprockets 95, carried by a shaft 96, mounted in bearings in frame uprights 97, and lower sprockets 98, fixed on a shaft 99, which runs in bearings in the same uprights. Shaft 99, has a sprocket 100, and chain 101, by which it is driven from shaft 58, so that it and the grooving conveyor are driven at the same speed as the feed conveyor.

The conveyor carries a series of grippers or chucks 102, (Fig. 12) spaced the same as the chucks of the feed conveyor 28, and shown in detail in Figs. 19 and 20. Each of these chucks includes a central outer serrated gripping member 103, adapted to grip the nut at the center of its central zone or belt, and inner grippers 104, spaced apart symmetrically with relation to the outer gripper in a lateral direction, giving a firm three-point support for the nut. Opposite chain links are connected by cross-bars or blocks 105 and 106 which, together with the links, constitute the frame or support of the gripping unit. One of the cross blocks 105, has a sleeve 107, in which a rod 108, is reciprocably mounted. At its outer end the rod carries an arcuate arm 109, supporting the outer gripper 103. Cross block 106, has sleeves 110 in which other rods 111, are reciprocably mounted, and the inner grippers are carried by the outer ends of these rods. The outer gripper is urged inward, and the inner grippers are urged outward, by springs 112 and 113. For gripper 103, a spring 112, is placed about the inner end of rod 108, and acts between cross block 105, and a collar 114, on the rod. For gripper 104, springs 113 are placed about the outward portions of rod 114, and act between the bases of the grippers and cross block 106. To retract the grippers at the time of receiving the nut, a rock shaft 115, is mounted in bearings in chain links 91. This rock shaft carries a short arm or lug 116, passing through a slot leading to sleeve 107 and located in a slot 117, in rod 108, and designed to engage the outer end (or upper end as viewed in Fig. 20) of the slot. The rock shaft also carries other arms or lugs 118, accommodated in slots 119, leading to sleeves 110, and having their ends located in slots 120, of rods 111, and adapted to engage the inner or lower ends of the slots. Desirably also in some cases more positive means, such as detent mechanism, is provided for retaining the grippers in firm contact with the nut. Such means includes spring pawls 121, secured to cross blocks 105 and 106, as by screws 122, and having their ends engaging serrations or ratchet formations 123, on rods 108 and 111. The pawls are operated by links 124, connected to lugs 125, on rock shaft 115, and to ears 126, formed on the pawls. The gripping mechanism is actuated by an arm 127, connected to one end of rock shaft 115, and having a roller 128, co-operating with a cam strip or rail 129, secured fixedly on the frame and including a radial portion or shoulder 130, and an arcuate portion 131.

Each chuck 102, as it reaches the uppermost position, passing around sprockets 95, as shown in Fig. 12, is "open"; that is, the grippers are retracted with respect to a central point and are held in this position by the cam roller running on the arcuate portion of the

cam rail, 129. The chuck is held open until it reaches a position to the left of shaft 96, thus properly locating the grippers with relation to a nut carried by the feed conveyor, and as the chuck of the feed conveyor is opened to release the nut, cam roller 128 passes away from the cam rail, permitting springs 112 and 113, to close the jaws of the chuck; that is, the springs move the outer and inner grippers toward the nuts, which is firmly clamped and held and carried forward for the grooving operation. During grooving, the grippers are again retracted in a similar way, by the action of a lower cam rail 129, while the nut is held in the chuck of the grooving mechanism; thereafter, the grippers again engage the nut, which passes up along the right-hand side of the grooving conveyor to a position at the right of shaft 96, Fig. 12. At this time one of the cracking mechanisms is in position at the same point to receive the nut, and grippers 103 and 104, are opened to release the nut, by cam roll 128, encountering the radial shoulder 130 of the cam rail which causes rock shaft 115, to be turned counter-clockwise as viewed in Fig. 20, whereupon lugs 116 and 118 engage the ends of the slots of the respective gripper rods 108, and 111, and move the grippers away from the nut center with accompanying compression of springs 112, and 113; and thereafter the grippers continue in "open" condition to nut-receiving position.

Because of the normal clearance between lugs 116 and 118, and the ends of their respective slots, and the position of links 124, whenever rock shaft 115 is rotated to release or open the grippers 103 and 104, the detents 121 are first moved outward away from engagement with the ratchets, thus permitting the rods to move; and in the reverse movement of the rock shaft, the rods first move under the impulse of springs 112 and 113, to engage the grippers with the nut, and shortly thereafter the positive detents 121 are permitted to reengage with their ratchets on the rods to hold the grippers positively in nut-engaging position.

The grooving mechanism is carried by plates 150 having hub sleeves 151 keyed on shaft 99, or otherwise positively secured as by set screws 152. Each of these discs or plates 150, carries a plurality of grooving mechanisms 153, spaced in accordance with the spacing of the chucks of the grooving conveyor as they pass about shaft 99; that is, with the proportions and arrangement shown, there are four sets of grooves carried by each plate, those of the two plates being of course axially opposite to act simultaneously on a nut. Each grooving mechanism includes as principal parts or groups, a chuck and a groover. The sets of opposite chuck devices carried by the respective plates each

constitutes a complete chuck or nut-holder. Each of such chuck devices includes a main or outer sleeve 154, having a portion 155, passing through the plate and also having a 5 flange 156, secured to the plate by screws 157. This sleeve (in addition to outer functions later referred to) serves as a bearing in which a second sleeve 158, is revolubly mounted in bushings 159, and secured against 10 end motion by a flange 160, and collar 161. A third or inner sleeve 162, is mounted for reciprocation within sleeve 158, the inner sleeve having at its inward end a collar 163, to limit outward movement, and also having 15 at the other end an annular shifting groove 164 formed between flanges 165. Sleeve 162, is connected to rotate with sleeve 158, by a spline 166. Within sleeve 162, a rod 167, is mounted for reciprocation and connected to 20 rotate with the sleeve by a spline 168. At its inner end this rod has a cup or chuck member 169, to engage the nut end. Within the sleeve the rod has a collar 170, and a spring 171, is located about the rod between 25 this collar and a screw plug 172, inserted in the outer end of the sleeve. Sleeves 162, with the chuck rods are reciprocated by a lever 175, (Fig. 17) having a fork 176, with 30 studs or trunnions 177, engaging in the shifting groove 164. The levers 175 of all the chuck mechanism, as best shown in Fig. 17, are fulcrumed at 178, on the outer face of the corresponding plate 150. The ends of 35 these levers away from the forks carry rollers 179, which cooperate with a cam track or rail 180 secured to a fixed frame member. As each chuck approaches a position approximately vertically below the shaft 99, the corresponding cam roll 179 is engaged by the 40 angularly forward end 181 of the cam rail, and thus through the lever, sleeve 162, is pushed inward; thus two opposite chuck cups are simultaneously engaged with the nut ends, and at about this time the conveyor 45 grippers 103 are released from the nut. Inward movement of sleeve 162, continues while the spring 171 is compressed additionally, applying to the nut sufficient pressure to hold it firmly and rotate it (by means to 50 be described) while the grooving operation is performed. Springs 171 also serve to compensate for varying nut-lengths, by yielding- 55 ly moving the chucks toward the nut center. Thereafter, as the chuck approaches a horizontal position, to the right of shaft 99, as viewed in Figs. 12 and 17, the cam roller passes away from the rearward end of the cam rail and sleeves 162 are retracted, as by 60 springs 182, first relaxing the spring pressure on the chucks and then retracting the chuck cups 169, from the nut as the latter is again grasped by grippers 103 and 104.

To rotate the nut during grooving sleeve 158, has on its outer end a gear 190 secured 65 by a key 191, and set screw 192. This gear

also forms a part of the cutter drive mechanism as later referred to.

While a single cutter would be sufficient for the grooving operation (that is for each end of the nut), preferably as shown, two 70 opposite cutters are provided in each of the combined gripping and grooving mechanisms. The cutters 8, are mounted on the inward ends of shafts (not shown) which are revolubly mounted in bearings 192, with 75 their axes vertical (or perpendicular to the axis of rod 167). The cutters are shaped to produce a proper groove-cross-section such as that above referred to and shown in Figs. 4 and 5. On the outer end of each of the 80 cutter shafts is a bevel pinion 193, engaging a pinion 194, on the inner end of a shaft 195, parallel to the axis of sleeve 154, and supported in bearings 196, on a cutter carrier 197, which also carries the cutter shaft bearings 192. Each shaft 195, also passes through a sleeve 197, in which it is slidably mounted, and is connected to rotate with the sleeve by a spline 198. Sleeves 197, are revolubly mounted in bearing sleeves 199, secured in apertures 200, of the plates 150, with suitable means such as a flange 201, and collar 202, to prevent end motion of each of the 85 sleeves 197. Each cutter carrier is reciprocably mounted in guides 210, in a slide 211. Each of these slides is also reciprocably mounted in guides 212, the guides for the two slides of each cutter mechanism, being located at opposite sides of the outer sleeve 154, above mentioned which forms a bearing 90 for sleeve 158, of the chuck mechanism. Each cutter carrier has one or more rods 213, passing through holes in a flange 214, formed on the corresponding slide 211, and springs 215, located about the rods between 95 said flange and the outer end of the carrier urge the latter inward in relation to the slide to an extent limited by collars 216, on the outer ends of the rods. The slides are actuated by levers 217, (Fig. 18) having forks 110 218, provided with studs or trunnions 219, engaging in sockets in flanges 214. These levers are fulcrumed at 220, on the respective plates 150, and carry at their outer ends cam rollers 221, cooperating with a cam rail or track 222, secured to a fixed frame member 223. Means such as springs 224, tend to 115 retract the levers and slides 211. As each cutting mechanism approaches a position below shaft 99, and about the time that the nut is 120 grasped by the chucks 169, cam rolls 221 become engaged with the cam tracks 222, and the levers are operated to move slides 211, inward, thus bringing the cutters in contact 125 with the nut with yielding pressure applied by springs 215, to the cutter carriers, and thereafter these springs continue to urge the carriers inward as the cutters form and complete the grooves in opposite ends of the nut. 129 The yielding movement of the cutter carriers,

urged by springs 215, also serves to compensate for variations in nut-length. Then as the cam rolls leave the cam rail the slides and cutter carriers are retracted by the action of springs 224, clearing the cutters from the nut, and at about the same time the chucks are retracted and the nut is again grasped by the grippers and carried on for delivery to the cracking mechanism.

10 For rotating the cutters one of the shafts 195,—specifically the inward one of each cutting mechanism—has revolvably mounted on an outer extension thereof a pinion 230. This pinion is also slidable on the shaft and 15 is controlled by a spring 231, located between the pinion and a collar 232, on the shaft end. Sleeve 197, in which the same shaft is mounted also has fixed thereon a pinion 233, and it and pinion 230 are provided with positive 20 clutch jaws 234. Pinion 233, engages gear 190, above mentioned which directly rotates the chuck and also engages another pinion 235, identical with pinion 233, above mentioned except for the clutch teeth and similarly 25 mounted with respect to sleeve 197, of the outer cutter driving shaft 195. Pinion 230, engages a gear 240, carried by or connected to a sleeve 241, which is revolvably mounted on the sleeve hub 151, of the adjacent plate 150, and gear 240, is driven by a 30 sprocket 242, keyed on its sleeve 211, and a chain 243, connects the sprocket to a sprocket on shaft 61, above mentioned, that is, to the primary drive shaft of the machine, which 35 runs at relatively high speed in relation to other parts of the mechanism, namely such parts as effect the driving of the feed and grooving conveyors.

The described driving arrangement provides for driving the chucks and cutters only during the cutting period and permitting them to come to rest in relation to their supporting plates except during cutting, in the following way: Pinion 230, is constantly 40 driven at relatively high speed by gears 240, having a face width enabling it to remain in mesh with the gear while moving slightly endwise. When the cutter slides are retracted, pinion 230 is moved by a shoulder 244, on shaft 195, outward, sufficiently to free its clutch teeth from engagement with those of pinion 233. Thereupon, driving of the cutters and chucks is discontinued. Just before the cutting action begins, as slides 211, and cutter carriers 196, are moved inward, with accompanying inward movement in sliding of shaft 195, through its sleeve 197, pinion 230, is moved axially along with the shaft until its teeth engage with the clutch teeth of pinion 233, and thereupon shaft 195, is driven directly by pinion 233, through sleeve 197; gear 190, is driven by pinion 233, to rotate the chuck 169, and pinion 235, connected to the outer cutter drive shaft 195, is driven by gear 190, the arrangement being such that the cut-

ters are rotated in a reverse direction with relation to the rotation of the chucks, thus providing for the most efficient cutting action. Spring 231, permits continued inward movement of shaft 195, during cutter feed 70 action.

In the arrangement of parts shown provision is made for forming the grooves during a nut travel which corresponds to approximately one-quarter rotation of shaft 99; but 75 evidently by simple modification, such as a re-arrangement of the cam rails 180, and 222, a longer cutting time may be provided for, corresponding, say to one-half or nearly one-half rotation of shaft 99 and plates 150. 80

After the grooves are cut, the nuts are freed from chucks 169, and again grasped by grippers 103 and 104, as previously described, and carried up to a point at the right of shaft 96, for delivery to grippers of one 85 of the chucks of the cracking mechanism.

Practically all of the cracking mechanism, as shown in Figs. 21 to 33 inclusive, is supported on or adjacent a shaft 300. This shaft is revolvably mounted in bearings 301, carried by frame uprights 302, Figs. 12 and 21. Shaft 300, is driven by a sprocket 303, on one end thereof, and a chain 304, from a sprocket 305, on a countershaft 306, connected by gears 307, to shaft 58, above mentioned, the sprocket drive ratio being such that the cracking mechanism as a whole is rotated with shaft 300, at a speed greater than the linear speed of the grooving conveyor, on account of the greater arcuate spacing of the cracking units as compared with the spacing of the chucks of the grooving conveyor. 100

Near each of the standards 302, and inwardly thereof, opposite wheels or plates 310, are fixed on the shaft 300, by means of their hubs 311, and keys or set screws 312. These wheels or plates may be reinforced by radial flanges 313. Each wheel supports a plurality of cracking units 314, these being spaced arcuately with regard to the diameter and speed of the cracking mechanism. In the present instance and to correspond with cracking mechanism as above described, there are at each side of the machine eight cracking mechanisms or units 314, each unit carried by one of the wheels 310, being axially opposite one of the other units so that two such units constitute a complete cracking mechanism. The cracking units carried by each wheel may be identical with the exception of the hammering mechanism included in the units of one wheel and omitted from those of the other. Corresponding to each wheel and its cracking units, is a cam drum, and these may be identical except for reversal of cam grooves, etc., due to their opposite locations in the machine and except for parts included in one of the drums for operating a hammer mechanism of the corresponding wheel and omitted from the other drum. 125 130

Thus, cam drum 315, located at the right hand side of the machine (looking from the rear, or from the right of Fig. 12) adjacent wheel 310, also located at that side of the 5 machine includes hammer operating mechanism and cracking units carried by the wheel include the hammer mechanism while cam drum 316, located at the left of the machine as similarly viewed omits the hammer 10 operating mechanism, and the cracking units correspondingly do not include hammering mechanism.

The peripheral parts of the drums are carried by webs 317, which have hubs 318, mounted 15 on portions of bearings 301, which support shaft 300, and secured against rotation as by splines 319, and set screws 320.

For the support of its cracking units, each wheel 310, has near its periphery apertures 20 321, and in each of these apertures is inserted an outer sleeve 322, having a flange 323, and screws 324, fixing the sleeve immovably to the wheel. A second sleeve 325, is mounted to slide in sleeve 322, its inward 25 movement (toward the left in Fig. 28) being limited by a collar 326. Sleeve 325, is irrevolvably connected to sleeve 322, by a spline 327. A third sleeve 328, is mounted for reciprocation in sleeve 325, and connected irrevolvably by a spline 329. A fourth sleeve 30 330, is mounted to slide in sleeve 328 and connected against rotation by a spline 331. A fifth sleeve 332, is mounted to slide in sleeve 330, and connected against rotation by a spline 333. A sixth sleeve 334, is mounted 35 to slide within sleeve 332, and connected thereto against rotation by a spline 335. A rod 336, which is a chuck rod, is arranged to reciprocate within the inner sleeve 334, and 40 rotation of this rod is immaterial. Of the stated sleeves, outer sleeve 322 serves only as a support. The second sleeve 325, has at its inner end an enlarged portion 337, from which project spaced arms or lugs 338, supporting the hammers and anvils. The third sleeve 328, has at its inward end an enlargement 339, fitting within that of sleeve 325, and carrying at its inner end gripper slide supports and other parts as later referred to.

45 The fourth sleeve 330, has at its inner end within the enlargement 339, of sleeve 328, a collar 340, to limit outward movement of sleeve 330, in relation to sleeve 328. The fifth sleeve 332, has at its inner end a coned head 341, for the operation of shell end or cap crushing grippers 342. On the inner end of rod 336 is a chuck 343, having a part spherical face 344, (Fig. 31) with a prong 345 at its center, to grip an end of the shelled meat. 50 The inner enlargement 339, of sleeve 328, has a flange 350 to which are connected angularly arranged guide plates 351. On each of these plates a slide 352 is mounted for reciprocation and secured by flanges 353, on 55 the plate. At its inner end each slide has a

straight, or axially directed portion 13, terminating in the gripper flange 14, previously referred to in the method description. The grippers of flange 14, are arcuate in the cross-axial plane, as best shown in Figs. 22 and 23. 70 At its outer end each guide plate 351, has a lug 360, and a rod 361, on the slide passes through a guide hole in the lug. A spring 362, about the rod urges the slide to move angularly downward and inward. 75

Within the inner ends of the guide plates, the shell cap gripping levers 342 are pivotally mounted in lugs 363. The inward ends of these levers have jaws or surfaces 364, to engage the periphery of the shell cap. In inactive position, the outer ends of the levers cooperate with the inner faces of gripper members 13. The gripping ends of levers 342, are urged to separate by springs 365, placed about studs 366, and engaging in sockets 367, 80 in inner faces of the guide plates. The outer ends of levers 342, have rollers 348, to cooperate with the cone 341, on the inner end of sleeve 332.

The inner end enlargement of sleeve 325, 85 carries the spaced pairs of lugs 338, above referred to. Anvil levers 368, are pivotally mounted between the lugs on pins 369. The outer end of each lever has a fork 370, and an anvil 371, is pivotally mounted in the fork on a stud 372. At the inward end of the anvil is a part spherical socket formation 373, which conforms approximately to the contour of a segment of the shell belt. The outward end of the anvil is formed as a head 374, to receive hammer blows. The fork 370, engages in recessed side portions 375, of the anvil between the inner and outer heads, so that the anvil has limited tilting movement in an axial plane. Radial motion of the anvils is 90 controlled by a hollow cone 380, cooperating with rollers 381, on the outward ends of levers 368. The cone 380, is secured to the inner end of a short sleeve 382, which is revolvably mounted on the outer fixed sleeve 322, above mentioned. Springs 383, normally urge the anvils to move inwardly. Sleeve 382, also carries a dished drum 384, to which is secured a cam ring 385, for operating the hammers. 95 The hammers 386, are mounted on the ends of levers 387, which are pivotally mounted between lugs 338, on pins 388. Desirably the hammers are revolvably mounted on reduced end portions of the levers, in order to equalize 100 wear. The hammers are urged inward by springs 389, connecting levers 387 to lugs 338. At its outer end each lever has a revolvable cam roller 390, cooperating with the cams 391, formed on the inner periphery of cam ring 105 385, above mentioned. 110

115 Drum 384, is rotated during a part of the complete rotation of the cracking unit about shaft 300, by a pinion 392 on sleeve 382, engaging a segmental internal gear 393, (Figs. 120 394, 125 395, 130 396, 131 397, 132 398, 133 399, 134 400, 135 401, 136 402, 137 403, 138 404, 139 405, 140 406, 141 407, 142 408, 143 409, 144 410, 145 411, 146 412, 147 413, 148 414, 149 415, 150 416, 151 417, 1378, 1113 1379, 1114 1380, 1115 1381, 1

12 and 21) which is secured in fixed position to frame members, as at 394.

The axial movement of sleeve 325 to move the anvils and hammers inward to active position, and to retract them therefrom, is controlled by a cam roller 400 on the outer collar 326 engaging in a cam groove 401, in drum 315.

The axial movement of sleeve 328, for the 10 operation of the shell belt compressing and disrupting grippers 14, is controlled in the following way:—

On the outer end of sleeve 330, and fixed against rotation thereon, is a cam supporting 15 body 402, which has a cam roller 403, engaging in a cam groove 404, of drum 315. The body is recessed at 405, to accommodate one 20 end of a spring 406, which is compressed between the end of sleeve 330, and collar 407, on 25 the outer end of sleeve 328. The reciprocation of sleeve 330, under control of the cam groove 404, indirectly effects the reciprocation of sleeve 328, which carries the shell belt grippers, under the control of other cam 30 mechanism 410. (See Fig. 25.) This includes a cam ring 411, revolvably mounted 35 on the body 402, and having on its inward end cam faces 412. The cam ring is normally rotated to inactive position by a spring 413, 40 tensioned between it and the supporting body 402. It is moved to active position by a lever 414, (Figs. 21, 24 and 25) having on its 45 end a cam roller 415, cooperating with a cam formation, of the corresponding drum 315 or 50 316. This cam formation 420, of drum 316, is at its inner end as sufficiently shown in Fig. 21, and the corresponding cam formation 420, of drum 315, is at an intermediate point of 55 its length, as shown in Fig. 21 and also in the 40 cross section, Fig. 24. This cam formation includes a part 421 of large radius and another part 422, of smaller radius, each of 60 these parts having an arc of approximately 180°, with a diagonal portion 423, connecting them at one point, and a radial portion or shoulder 424, connecting them at another point, where the rollers drop off of the large 65 radius cam portion 421. The cam faces 412 of cam ring 411, cooperate with cam 430, carried by a flange 431, secured to the outer end 70 of sleeve 328. The cam supporting body 402, has circularly spaced pins 435, extending through holes 436 in flange 431, and springs 437, located on the pins, urge sleeve 328 to 75 move inward in relation to sleeve 330.

Sleeve 332 has connected to collar 407, at its outer end, a cam roller 450, engaging in a cam groove 451, to control cap grippers 342 by the movement of cone 341.

Sleeve 334 has connected to a collar 460 at its outer end, a cam roller 461, engaging in a cam groove 462 in drum 315, to operate the chuck cup 343 at the inner end of rod 336 through the agency of a spring 465, 60 which acts between a collar 466 and a screw 65

70 plug 467, inserted in the end of sleeve 334. Rod 336 has a stop collar 468 on its outer end.

The cracking mechanism rotates clockwise with shaft 300 as viewed in Fig. 12. 75 When each cracking instrumentality, each of which consists of the opposite units carried by the wheels 310, as above described, reaches a position horizontally at the left of the shaft, parts of the opposite units are positioned as shown in Fig. 26; that is the grippers are retracted horizontally outward and are also moved to their farthest radially inward position by reason of slides 352 being 80 moved down on their guide plates by the action of springs 362, so that the slide members 13 and grippers 14 are in endwise abutting relation, or in other words, the grippers form a closed circular flange which is ready to engage in the adjacent nut groove when 85 sleeve 328 carrying the grippers as a unit is moved inward (toward the nut center). Sleeve 325 carrying the anvil and hammer mechanism is retracted outward, removing the hammers and anvils from the zone or 90 plane of nut movement so that they do not interfere with the positioning of the nut by the grooving conveyor for reception by the grippers of the cracking mechanism. Sleeve 328 is now moved inward, toward the nut 95 center, by cam groove 404, acting on the cam roller 403, the position of the grippers being otherwise unchanged, and the opposite rings of gripper flanges enter the nut grooves to support the nut, whereupon the grippers of 100 the grooving conveyor are operated to release the nut and the nut is carried on in a circular path about shaft 300, the relatively high speed of rotation serving to get the nut away from the grooving conveyor grippers. 105 As the nut is thus advanced, the opposite sleeves 328 are urged convergently to apply pressure to the ends of the shell belt and bulge it, as referred to in the method described, the grippers being prevented during this action from moving radially by their engagement in the under-cut shell grooves. 110 (See Fig. 27.) Just before pressure is applied as stated to bulge the belt, sleeve 325 is moved axially inward to position the anvils radially opposite the shell belt and at the same time the movement of cam rolls 381 outwardly in their controlling cone 380 permits the anvils under the action of springs 383 to move inward and engage the shell belt 115 in approximately the position shown in Fig. 28. At the same time the cam rolls of hammer levers 387 have been placed in the plane of the cam ring 385 as also shown in Fig. 28. At this time pinions 392 encounter the teeth of the segmental fixed gear 393, and the hammering cams are rapidly rotated, causing the hammers to strike forcibly on the anvils and crack the shell belt, while at 120 the same time sleeve 328 is moved farther 125

inward by the powerful action of the cams 412 and 430, operated by the rollers of the levers 414 encountering the slant face 423 of their controlling cams (Fig. 24), this forcible inward movement of the sleeves causing slide supporting plates 351 to move inward (toward the nut center), thus splitting and disrupting the shell belt, the beginning of this action being shown in Fig. 29 and later 10 stages in Figs. 30 and 31. The inward movement of sleeve 328 to the position in Fig. 29 and radial outward movement of grippers 14 permit the gripping ends of the cap crushing levers 342 to move radially outward, and these grippers are thus positioned upon the edges of the shell caps as shown in Fig. 29. Sleeves 332 are then moved inward by cam grooves 451, and their cones 341 acting on the rollers 348, spread the outward 15 ends of the cap crushing levers and move their inner ends convergently to crush the caps as shown in Fig. 30. Thereafter, sleeves 334 are moved inward, causing the chuck cups on the inner ends of rods 336 to engage 20 the ends of the nut meat 4, Fig. 31, springs 465 being in this movement compressed to cause the chucks to grip and hold the meat with resilient pressure; various parts are returned to inactive positions by actions of the 25 cam mechanism as will readily be understood, the meat holding chucks being retracted at about the time that the cracking instrumentality reaches the lower position, under shaft 300. The kernels are thus discharged 30 by gravity, and if desired, a carry off conveyor may be provided, consisting of a belt 500, supported on a pulley 501 (and another pulley at a convenient location—not shown), this being driven as by sprockets and a chain 35 502 from shaft 58. The belt may be provided with blades or spacers 503, so that each shelled kernel is dropped into a separate pocket or compartment of the conveyor.

Fig. 33 shows diagrammatically, with appropriate legends, the action of the cams of the cracking mechanism.

Springs 496 and 437 are provided, in connection with the arrangement of cams 412 and 430, to adapt the belt gripping mechanism to nuts of varying length, and to secure quick inward movement of the grippers into the shell grooves. Thus when cam ring 411 is in idle position, with rolls 415 of lever 414 in the "low" part of its cam, as shown in Fig. 21, springs 437 urge sleeve 328 to the left in relation to sleeve 330 and grippers 14 are positioned inwardly, to engage a "short" nut, cam members 430 and 412, being only partly "meshed" or telescoped, as also shown in Fig. 21. If the nut is longer, the grippers engage it sooner, in their inward movement; and after such engagement, the cams 430 and 412 are more fully "meshed" as sleeve 430 slides inward, with accompanying compression of springs 437, which are "weaker" than

springs 362 which control the action of slides 352. Cam groove 404 which effects the inward movement of sleeve 330, has a sharply offset portion 404^a, Fig. 32, to move the grippers 14 quickly into the shell grooves, and spring 406 serves to urge the sleeve inward, and "assist" the cam roll 403 to follow, or pass through, this offset 404^a of its groove without jamming.

Fig. 34 shows a modification in which the anvils 371 are more positively operated by levers 600 fulcrumed at 601 on the inner end of fixed sleeve 602, which is similar to sleeve 322 of Fig. 28. The outward ends of levers 600 are normally urged inward by springs 603 located about rods 604, passing through holes in a guide flange 605 secured to sleeve 602. The inward ends of the levers cooperate with the cam rolls 381 on the outward ends of the anvil levers 368 so that as sleeve 325 carrying the hammering mechanism is moved inward, rolls 381 cooperate with the spring urged levers 600 to quite positively move the anvils inward to engage the shell belt. Springs 606 serve to move the anvils outward 90 when retracted from active position.

I claim:

1. A method of shelling large hollow nuts such as coconuts, comprising severing and separating the shells into a belt and caps by forming annular grooves in the nut near its ends, supporting the belt by end pressure, bulging the belt to separate it from the meaty portions hammering the belt to crack it, and thereafter removing the caps.

2. A method of shelling large hollow nuts such as coconuts, comprising severing and separating the shells into a belt and caps by forming annular grooves in the nut near its ends, supporting the belt by end pressure, bulging the belt to separate it from the meaty portions, hammering the belt to crack it, and thereafter crushing the caps by inwardly directed edge pressure.

3. A method of shelling large hollow nuts such as coconuts, comprising severing and separating the shells into a belt and caps by forming annular grooves in the nut near its ends, supporting the belt by end pressure, bulging the belt to separate it from the meaty portions, hammering the belt to crack it, disrupting the belt by outwardly directed force, and thereafter removing the caps.

4. A method of shelling large hollow nuts such as coconuts, comprising severing and separating the shells into a belt and caps by forming annular grooves in the nut near its ends, supporting the belt by end pressure, bulging the belt to separate it from the meaty portions, hammering the belt to crack it, disrupting the belt by outwardly directed force, and thereafter crushing the caps by inwardly directed edge pressure.

5. A method of shelling large hollow nuts such as coconuts, comprising severing and

separating the shells into a belt and caps by forming annular grooves in the nut near its ends, forcefully gripping the grooves to bulge the belt, hammering the belt to crack it, and thereafter removing the caps.

6. A method of shelling large hollow nuts such as coconuts, comprising severing and separating the shells into a belt and caps by forming annular grooves in the nut near its ends, forcefully gripping the grooves to bulge the belt, hammering the belt to crack it, and thereafter crushing the caps by inwardly directed edge pressure.

7. A method of shelling large hollow nuts such as coconuts, comprising severing and separating the shells into a belt and caps by forming annular grooves in the nut near its ends, forcefully gripping the grooves to bulge the belt, hammering the belt to crack it, applying pressure against the grooves in generally radial outward directions to disrupt the belt, and thereafter removing the caps.

8. A method of shelling large hollow nuts such as coconuts, comprising severing and separating the shells into a belt and caps by forming annular grooves in the nut near its ends, forcefully gripping the grooves to bulge the belt, hammering the belt to crack it, applying pressure against the grooves in generally radial outward directions to disrupt the belt, and thereafter crushing the caps by inwardly directed edge pressure.

9. A nut shelling machine comprising means for producing annular grooves in a succession of large hollow nuts such as coconuts near ends thereof, defining in the shell thereof a belt and end caps, means for thereafter supporting the shell by end pressure and breaking the belt by hammering, and means acting thereafter to crush the end caps by inwardly directed edge pressure.

10. A nut shelling machine comprising means for producing annular grooves in a succession of large hollow nuts such as coconuts near ends thereof, defining in the shell thereof a belt and end caps, grippers arranged for movement toward the equator of the belt and also for generally outward radial movement, means for inserting the grippers in the grooves and moving them toward the equator to bulge the belt, hammering means, means for applying the hammering means to the belt to crack it, and means acting thereafter to move the grippers radially outward to disrupt the belt.

11. A nut shelling machine comprising means for producing annular grooves in a succession of large hollow nuts such as coconuts near ends thereof, defining in the shell thereof a belt and end caps, grippers arranged for movement toward the equator of the belt and also for generally outward radial movement, means for inserting the grippers in the grooves and moving them toward

the equator to bulge the belt, hammering means, means for applying the hammering means to the belt to crack it, and means acting thereafter to move the grippers radially outward to disrupt the belt, and means acting thereafter to remove the end caps.

12. A nut shelling machine comprising means for producing annular grooves in a succession of large hollow nuts such as coconuts near ends thereof, defining in the shell thereof a belt and end caps, grippers arranged for movement toward the equator of the belt and also for generally outward radial movement, means for inserting the grippers in the grooves and moving them toward the equator to bulge the belt, hammering means, means for applying the hammering means to the belt to crack it, and means acting thereafter to move the grippers radially outward to disrupt the belt, and means acting thereafter to crush the end caps by inwardly directed edge pressure.

13. A nut shelling machine comprising means for producing annular grooves in a succession of large hollow nuts such as coconuts near ends thereof, defining in the shell thereof and end caps, grippers arranged for movement toward the equator of the belt and also for generally outward radial movement, means for inserting the grippers in the grooves and moving them toward the equator to bulge the belt, hammering means, means for applying the hammering means to the belt to crack it, and means acting thereafter to move the grippers radially outward to disrupt the belt, and means acting thereafter to crush the end caps by inwardly directed edge pressure.

14. A nut shelling machine comprising means for producing annular grooves in a succession of large hollow nuts such as coconuts near ends thereof, defining in the shell thereof and end caps, grippers arranged for movement toward the equator of the belt and also for generally outward radial movement, means for inserting the grippers in the grooves and moving them toward the equator to bulge the belt, hammering means, means for applying the hammering means to the belt to crack it, and means acting thereafter to move the grippers radially outward to disrupt the belt, and means acting thereafter to remove the end caps, and means acting thereafter to support and deliver the shelled meat.

15. A nut shelling machine comprising means for producing annular grooves in a succession of large hollow nuts such as coconuts near ends thereof, defining in the shell thereof a belt and end caps, grippers arranged for movement toward the equator of the belt and also for generally outward radial movement, means for inserting the grippers in the grooves and moving them toward the equator to bulge the belt, hammering means,

means for applying the hammering means to the belt to crack it, means acting thereafter to move the grippers radially outward to disrupt the belt, means acting thereafter to crush the end caps by inwardly directed edge pressure, and means acting thereafter to support and deliver the shelled meat.

16. A nut shelling machine comprising means for advancing a succession of large hollow nuts such as coconuts, means for producing annular grooves in the nut near ends thereof defining in the shells thereof a belt and end caps, means for thereafter supporting the shell and breaking the belt by hammering, and means acting thereafter to remove the end caps.

17. A nut shelling machine comprising means for advancing a succession of large hollow nuts such as coconuts, means for producing annular grooves in the nut near ends thereof defining in the shells thereof a belt and end caps, means for thereafter supporting the shell and breaking the belt by hammering, and means acting thereafter to crush the end caps by inwardly directed edge pressure.

18. A nut shelling machine comprising means for advancing a succession of large hollow nuts such as coconuts, means for producing annular grooves in the nut, near ends thereof defining in the shells thereof a belt and end caps, grippers arranged for movement toward the equator of the belt and also for generally outward radial movement, means for inserting the grippers in the grooves and moving them toward the equator to bulge the belt, hammering means, means for applying the hammering means to the belt to crack it, and means acting thereafter to move the grippers radially outward to disrupt the belt.

19. A nut shelling machine comprising means for advancing a succession of large hollow nuts such as coconuts, means for producing annular grooves in the nut near ends thereof defining in the shells thereof a belt and end caps, grippers arranged for movement toward the equator of the belt and also for generally outward radial movement, means for inserting the grippers in the grooves and moving them toward the equator to bulge the belt, hammering means, means for applying the hammering means to the belt to crack it, means acting thereafter to move the grippers radially outward to disrupt the belt, and means acting thereafter to remove the end caps.

20. A nut shelling machine comprising means for advancing a succession of large hollow nuts such as coconuts, means for producing annular grooves in the nut near ends thereof defining in the shells thereof a belt and end caps, grippers arranged for movement toward the equator of the belt and also for generally outward radial movement,

means for inserting the grippers in the grooves and moving them toward the equator to bulge the belt, hammering means, means for applying the hammering means to the belt to crack it, means acting thereafter to move the grippers radially outward to disrupt the belt, and means acting thereafter to crush the end caps by inwardly directed edge pressure.

21. A nut shelling machine comprising means for advancing a succession of large hollow nuts such as coconuts, means for producing annular grooves in the nut near ends thereof defining in the shells thereof a belt and end caps, grippers arranged for movement toward the equator of the belt and also for generally outward radial movement, means for inserting the grippers in the grooves and moving them toward the equator to bulge the belt, hammering means, means for applying the hammering means to the belt to crack it, and means acting thereafter to move the grippers radially outward to disrupt the belt, end cap grippers arranged to engage the edges of the caps, and means for moving the grippers convergently to crush the caps.

22. A machine of the character described comprising a feed conveyor adapted to advance successive nuts laterally with respect to their axes, grooving mechanism comprising a conveyor having grippers arranged to receive the nuts from the feed conveyors and means for forming undercut annular grooves in the nuts near their ends defining a belt and end caps in each shell, and cracking mechanism comprising an annularly spaced series of cracking instrumentalities, each including grippers adapted to engage in the shell grooves and receive the nuts from the grooving conveyor and advance them for cracking, means for moving the grippers toward the nut equator to bulge the shell belt, hammering means, means for advancing the hammering means to active position and operating such means to crack the bulged belt, and means for moving the grippers generally radially outward to disrupt the belt.

23. A machine of the character described comprising a feed conveyor adapted to advance successive nuts laterally with respect to their axes, grooving mechanism comprising a conveyor having grippers arranged to receive the nuts from the feed conveyors and means for forming undercut annular grooves in the nuts near their ends defining a belt and end caps in each shell, and cracking mechanism comprising an annularly spaced series of cracking instrumentalities, each including grippers adapted to engage in the shell grooves and receive the nuts from the grooving conveyor and advance them for cracking, means for moving the grippers toward the nut equator to bulge the shell belt, hammering means, means for advancing the hammer-

ing means to active position and operating such means to crack the bulged belt, means for moving the grippers generally radially outward to disrupt the belt, end cap grippers, and means for engaging said grippers with edges of the caps and moving them convergently inward to crush the caps.

24. A machine of the character described comprising a feed conveyor adapted to advance successive nuts laterally with respect to their axes, grooving mechanism comprising a conveyor having grippers arranged to receive the nuts from the feed conveyors and means for forming undercut annular grooves in the nuts near their ends defining a belt and end caps in each shell, and cracking mechanism comprising an annularly spaced series of cracking instrumentalities, each including grippers adapted to engage in the shell grooves and receive the nuts from the grooving conveyor and advance them for cracking, means for moving the grippers toward the nut equator to bulge the shell belt, hammering means, means for advancing the hammering means to active position and operating such means to crack the bulged belt, means for moving the grippers generally radially outward to disrupt the belt, with the addition that the hammering mechanism comprises anvils and hammers and means for reciprocating the hammers radially to strike the anvils while the latter are engaged with the nut shell belt.

25. A machine of the character described comprising a feed conveyor adapted to advance successive nuts laterally with respect to their axes, grooving mechanism comprising a conveyor having grippers arranged to receive the nuts from the feed conveyors and means for forming undercut annular grooves in the nuts near their ends defining a belt and end caps in each shell, and cracking mechanism comprising an annularly spaced series of cracking instrumentalities, each including grippers adapted to engage in the shell grooves and receive the nuts from the grooving conveyor and advance them for cracking, means for moving the grippers toward the nut equator to bulge the shell belt, hammering means, means for advancing the hammering means to active position and operating such means to crack the bulged belt, means for moving the grippers generally radially outward to disrupt the belt, end cap grippers, and means for engaging said grippers with edges of the caps and moving them convergently inward to crush the caps, with the addition that the hammering mechanism comprises anvils and hammers and means for reciprocating the hammers radially to strike the anvils while the latter are engaged with the nut shell belt.

26. A machine of the character described comprising a feed conveyor adapted to advance successive nuts laterally with respect

to their axes, grooving mechanism comprising a conveyor having grippers arranged to receive the nuts from the feed conveyors and means for forming undercut annular grooves in the nuts near their ends defining a belt and end caps in each shell, and cracking mechanism comprising an annularly spaced series of cracking instrumentalities, each including grippers adapted to engage in the shell grooves and receive the nuts from the grooving conveyor and advance them for cracking, means for moving the grippers toward the nut equator to bulge the shell belt, hammering means, means for advancing the hammering means to active position and operating such means to crack the bulged belt, means for moving the grippers generally radially outward to disrupt the belt, with the addition that the hammering mechanism comprises anvils and hammers, and rotary cam means for actuating the hammers.

27. A machine of the character described comprising a feed conveyor adapted to advance successive nuts laterally with respect to their axes, grooving mechanism comprising a conveyor having grippers arranged to receive the nuts from the feed conveyors and means for forming undercut annular grooves in the nuts near their ends defining a belt and end caps in each shell, and cracking mechanism comprising an annularly spaced series of cracking instrumentalities, each including grippers adapted to engage in the shell grooves and receive the nuts from the grooving conveyor and advance them for cracking, means for moving the grippers toward the nut equator to bulge the shell belt, hammering means, means for advancing the hammering means to active position and operating such means to crack the bulged belt, means for moving the grippers generally radially outward to disrupt the belt, with the addition that the hammering mechanism comprises anvils and hammers and means for reciprocating the hammers radially to strike the anvils while the latter are engaged with the nut shell belt.

28. A machine of the character described comprising a feed conveyor having spaced chucks, each adapted to engage ends of a nut such as a coconut and arranged to advance successive nuts laterally with respect to their axes, means for operating the chucks, grooving mechanism comprising a conveyor having chucks arranged to receive the nuts from the feed conveyor, and cutters for forming undercut annular grooves in the nuts near their ends defining a belt and end caps in each shell, and cracking mechanism comprising an annularly spaced series of cracking instrumentalities, each including grippers adapted to engage in the shell grooves and receive the nuts from the grooving conveyor and advance them for cracking, means for

- moving the grippers toward the nut equator to bulge the shell belt, hammering means, means for advancing the hammering means to active position and operating such means 5 to crack the bulged belt, means for thereafter moving the grippers generally radially outward to disrupt the belt.
29. A machine of the character described comprising a feed conveyor having spaced 10 chucks, each adapted to engage ends of a nut such as a coconut and arranged to advance successive nuts laterally with respect to their axes, means for operating the chucks, grooving mechanism comprising a conveyor having 15 chucks arranged to receive the nuts from the feed conveyor, and cutters for forming undercut annular grooves in the nuts near their end defining a belt and end caps in each shell, and cracking mechanism comprising an 20 annularly spaced series of cracking instrumentalities, each including grippers adapted to engage in the shell grooves and receive the nuts from the grooving conveyor and advance them for cracking, means for moving 25 the grippers toward the nut equator to bulge the shell belt, hammering means, means for advancing the hammering means to active position and operating such means to crack the bulged belt, means for thereafter moving 30 the grippers generally radially outward to disrupt the belt, and cap grippers, and means for engaging said grippers with edges of the caps and moving them convergently inward to crush the caps.
30. Feed means for nut cracking machines of the character described, comprising a continuous conveyor and a plurality of spaced 35 chucks thereon, each chuck including opposite cupped members to engage the ends of a nut, means acting at a point in conveyor travel to open the chucks, detents for retaining the chucks in open position, and manually operated means for releasing the detents to close the chucks after insertion of nuts 40 therein.
31. Feed means for nut cracking machines of the character described, comprising a continuous conveyor having a long stretch to permit a plurality of workmen to have access thereto, and a plurality of spaced chucks 45 thereon, each chuck including opposite cupped members to engage the ends of a nut, means acting at a point in conveyor travel to open the chucks, detents for retaining the chucks in open position, and manually operated means for releasing the detents to close the chucks after insertion of nuts therein.
32. Grooving mechanism for nut shelling 50 machines of the character described, comprising a conveyor, and grooving mechanism including a plurality of circularly mounted grooving instrumentalities, and means for operating them in coordination with the 55 movement of nuts advanced by the conveyor to produce annular grooves in the nuts near the ends thereof.
33. Grooving mechanism for nut shelling machines of the character described, comprising a conveyor having a spaced series of grippers to engage belt portions of nut shells and advance the nuts laterally of their axes, means for operating the grippers, and grooving mechanism including a plurality of circularly mounted grooving instrumentalities, 70 and means for operating them in coordination with the movement of nuts advanced by the conveyor to produce annular grooves in the nuts near the ends thereof.
34. Cracking mechanism for nut shelling 75 machines of the character described, comprising a plurality of cracking instrumentalities arranged to move in a circuitous course, and each comprising segmental grippers arranged for inward movement to engage in a nut shell groove and generally radial movement to disrupt the shell belt, and shell cap gripping members and means for operating them to engage the edges of the shell caps and crush them by inward movement.
35. Cracking mechanism for nut shelling 80 machines of the character described, comprising a plurality of cracking instrumentalities arranged to move in a circuitous course, and each comprising segmental grippers arranged for inward movement to engage in a nut shell groove and generally radial movement to disrupt the shell belt, and shell cap gripping members and means for operating them to engage the edges of the shell caps and 85 crush them by inward movement, and cracking means to operate on the shell belts.
36. Cracking mechanism for nut shelling 90 machines of the character described, comprising a plurality of cracking instrumentalities arranged to move in a circuitous course, and each comprising segmental grippers arranged for inward movement to disrupt the shell belt, and shell cap gripping members and means for operating them to engage the 95 edges of the shell caps and crush them by inward movement, said cracking means including anvils to engage the shell belts, and hammers to strike the anvils.
37. Cracking mechanism for nut shelling 100 machines of the character described, comprising a plurality of cracking instrumentalities arranged to move in a circuitous course, and each comprising segmental grippers arranged for inward movement to disrupt the shell belt, and the shell cap gripping members and means for operating them to engage the edges of the shell caps and crush them by inward movement, said cracking means including anvils to engage the shell belts, 105 and hammers to strike the anvils, and rotary cam means for operating the hammers.
38. Cracking mechanism for nut shelling 110 machines of the character described, comprising a plurality of cracking instrumentalities

- ties arranged to move in a circular course, and each comprising opposed units, each unit including segmental grippers arranged for inward movement to engage in a nut shell groove and generally radial movement to disrupt the shell belt, and shell cap grippers and means for operating them to engage the edges of shell caps and crush them by inward movement.
39. Cracking mechanism for nut shelling machines of the character described, comprising a plurality of cracking instrumentalities arranged to move in a circular course, and each comprising opposed units, each unit including segmental grippers arranged for inward movement to engage in a nut shell groove and generally radial movement to disrupt the shell belt, and shell cap grippers and means for operating them to engage the edges of shell caps and crush them by inward movement, and the cracking units of all of said instrumentalities at one side of the machine also including cracking means to operate on the shell belts.
40. Cracking mechanism for nut shelling machines of the character described, comprising a plurality of cracking instrumentalities arranged to move in a circular course, and each comprising opposed units, each unit including segmental grippers arranged for inward movement to engage in a nut shell groove and generally radial movement to disrupt the shell belt, and shell cap grippers and means for operating them to engage the edges of the shell caps and crush them by inward movement, and the cracking units of all of said instrumentalities at one side of the machine also including cracking means to operate on the shell belts, said cracking mechanism including anvils to engage the shell belts, and hammers to strike the anvils.
41. Cracking mechanism for nut shelling machines of the character described, comprising a plurality of cracking instrumentalities arranged to move in a circular course, and each comprising opposed units, each unit including segmental grippers arranged for inward movement to engage in a nut shell groove and generally radial movement to disrupt the shell belt, and shell cap grippers and means for operating them to engage the edges of the shell caps and crush them by inward movement, and the cracking units of all of said instrumentalities at one side of the machine also including cracking means to operate on the shell belts, said cracking mechanism including anvils to engage the shell belts, and hammers to strike the anvils, and rotary cam means for operating the hammers.
42. A method of shelling large nuts such as coconuts, including severing and separating the shell into a belt and caps by forming annular grooves in the nut near its ends, removing the belt by forcing its edges radially outward, and thereafter removing the caps by crushing their edges radially inward.
43. A method of shelling large nuts such as coconuts, including severing and separating the shell into a belt and caps by forming annular grooves in the nut near its ends, and removing the belt by forcing its edges radially outward.
44. In a method of shelling large nuts such as coconuts, the steps of cutting the shell into zones and thereafter loosening each zone from the meat by applying pressure to the zone to increase its convexity.
- In testimony whereof I affix my signature.
- HUGH C. MacDOUGALL.
